UNITED STATES PATENT OFFICE

160,382

APRON

Saul Goldstein, Los Angeles, Calif.

Application August 15, 1949, Serial No. 4,517

Term of patent 3½ years

(Cl. D3—26)

To all whom it may concern:

Be it known that I, Saul Goldstein, a citizen of the United States, residing at Los Angeles, in the county of Los Angeles, State of California, have invented a new, original, and ornamental Design for Apron, of which the following is a specification, reference being had to the accompanying drawing, forming a part thereof.

Figure 1 is a front view of an apron, showing my new design.

Figure 2 is a perspective view thereof as worn.

The dominant feature of my design resides in the bib or bust-covering portion of the apron, including an elastic contained in the upper curved marginal edge thereof.

I claim:

The ornamental design for an apron, as shown and described.

SAUL GOLDSTEIN.
